DESIGN FOR LEATHER

Lester F. Peabody, Girard, Ohio, assignor to The Ohio Leather Company, Girard, Ohio, a corporation of Ohio

Application January 12, 1935, Serial No. 54,830

Term of patent 3½ years

To all whom it may concern:

Be it known that I, Lester F. Peabody, a citizen of the United States of America, residing at Girard, in the county of Trumbull and State of Ohio, have invented a new, original, and ornamental Design for Leather, of which the following is a specification, reference being had to the accompanying drawing, forming part thereof.

In said drawing,

Fig. 1 is a plan view of a piece of leather showing my new design; the ornamentation shown thereon is to be extended over any desired area; and

Fig. 2 is a section taken on line 2—2 of Fig. 1.

I claim:

The ornamental design for leather, substantially as shown and described.

In testimony whereof I affix my signature.

LESTER F. PEABODY.
